Primary Examiner — Thomas Johannes*Assistant Examiner* — Shawn T Gingrich(74) *Attorney, Agent, or Firm* — CARR Law Firm PLLC(57) **CLAIM**

We claim the ornamental design for a male electrical connector, as shown and described.

DESCRIPTION

FIG. 1 is a, top, right, front perspective view of a male electrical connector;

FIG. 2 is a bottom, left, rear perspective view thereof;

FIG. 3 is a top, left, rear perspective view thereof;

FIG. 4 is a bottom, right, front perspective view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a left side elevation view thereof; and,

FIG. 10 is a right side elevation view thereof.

The broken line portion of the figure drawings is included to show portions of the article that form no part of the claimed design.
